UNITED STATES PATENT OFFICE.

SAMUEL R. BRADY, OF GRANBY, MISSOURI.

CAR-COUPING.

SPECIFICATION forming part of Letters Patent No. 259,856, dated June 13, 1882.

Application filed April 7, 1882. (No model.)

To all whom it may concern:

Be it known that I, SAMUEL R. BRADY, a citizen of the United States of America, residing at Granby, in the county of Newton and State 5 of Missouri, have invented certain new and useful Improvements in Car-Couplers; and I do hereby declare the following to be a full, clear, and exact description of the invention, such as will enable others skilled in the art to 10 to which it appertains to make and use the same, reference being had to the accompanying drawing, and to letters or figures of reference marked thereon, which form a part of this specification.

15 The drawing illustrates in perspective a car-coupler constructed in accordance with my invention.

A represents the lower portion of a car to which, in the usual locations and manner, are 20 secured the brackets B B B, of usual construction, for the support and attachment of the coupler.

Between the usual buffer-spring, C, and the head of the draw-bar F is a universal coupling, D, which permits a free movement of the draw-bar within its bracket or strap in lateral and vertical directions, the former to allow easy passage of the cars around curves, and the latter to adapt the coupler to be used with 25 30 cars of different heights, which latter adaptation is facilitated by means of the block E, which is mortised at its ends to embrace the sides of the bracket, as shown at a, and which is thicker at one edge than at the other, while 35 the bottom of the bracket is internally slanted, so that by raising the draw-bar and lifting the block from its seat and reversing it the thicker edge is brought to the front, thus elevating the head of the draw-bar. Additional 40 or separate blocks either of uniform or varying thickness, like that shown, may be inserted to elevate the bar to any desired height.

The head of the draw-bar is hollow, and the 45 link G is extended beyond the pin-hole g, so that it strikes against a bell-crank lever, f, pivotally supported upon the head at f'.

To the upper arm of the lever f, at f², is pivotally attached the coupling-pin H, which 50 passes through the upper and lower surfaces of the head, as shown in dotted lines.

The outer end of the upper arm of lever f is beveled to co-operate with the latch-plate or catch f³, the upper end of which is beveled 55 in like manner.

The catch is pivotally supported at f⁴, and extended rearwardly beneath the upper arm of lever f nearly to the pin H, and at one side thereof to a point beyond the pin, and at this point is pivotally attached, or it may be rigidly secured, to a tripping-lever, f⁵, which, by the hand-rod I attached to its rear end, may be lifted to throw the catch f³ off the upper arm of lever f, when the rear extension of the catch raises the pin from the link, and thus uncouples the car.

I have added a spring, J, in this instance, coiled beneath the lever f, whereby upon the release of the lever f from the catch the pin is automatically withdrawn and the lever held in 70 position to be operated to couple the link when next introduced into the head, and thus the coupler is automatically always set for operation. If it is desired to retain the pin in an elevated and non-operative position, the hand-rod I is secured in an elevated position by any 75 suitable means.

It will be seen that the shape of the link permits a slight lateral movement thereof in the head, which is desirable in rounding curves, 80 and that the enlarged central portion, g', of the link limits its entrance into the head to such a distance that no destructive force of two cars coming together in the act of coupling can be exerted against the lever f and 85 the connected mechanism.

Having described my invention, what I claim as new, and desire to secure by Letters Patent, is—

1. The combination of the draw-bar F, pin 90 H, lever f, catch f³, lever f⁵, rod I, and spring J, with the link G, having the extended ends and central enlarged portion, g', substantially as shown and described.

2. The combination of the draw-bar F, having the universal joint D, the bracket B, and the beveled mortised block E, substantially as shown and described.

3. The combination of the draw-head, the bell-crank lever, the catch-plate and the tripping-lever, the catch-plate being adapted to retain the pin in a depressed position, and the rear extension of the catch being adapted to lift the pin from the link, substantially as shown and described.

In testimony whereof I affix my signature in presence of two witnesses.

Witnesses: SAMUEL R. BRADY,
E. B. STOCKING,
C. A. JOHNSON.
